SHUTTLE-MOTION FOR LOOMS.

No. 829,376.

Specification of Letters Patent.

Patented Aug. 21, 1906.

Original application filed July 21, 1904, Serial No. 217,462. Divided and this application filed August 16, 1905. Serial No. 274,392.

To all whom it may concern:

Be it known that I, GIOVANNI GIUSSANI, engineer, a subject of the King of Great Britain and Ireland, residing at 6 Church Gardens, Ealing, in the county of London, England, have invented certain new and useful Improvements in Shuttle-Motions for Looms, of which the following is a specification.

This invention, which originally formed part of my patent application Serial No. 217,462, dated July 21, 1904, of which this is a division, relates to a shuttle-motion suitable for a loom for making sheets or nets of heavy comparatively rigid material, such as helically-twisted wire.

Figure 1 is a transverse section showing the mechanism for moving the shuttle. Fig. 2 is a plan view of the same with portions of the frame in section, and Fig. 3 is a detail view drawn to an enlarged scale.

In the loom for which this shuttle-motion is primarily intended each warp *a* passes through a tube *c*, which tubes form the shed through which the shuttle-drum *d* is passed. The tubes *c* are arranged in two series alternating with each other, those of one series being hinged to one heald and those of the other series to a second heald, as shown in Fig. 2. The tubes are held from moving laterally by means of suitable comb arrangements, which when the healds are moved in opposite directions to make the shed, as in a common loom, rest on the moving tubes.

The weft-wire is wound on the drum *d*, mounted to rotate in a horizontal plane on a slide *d'*, Fig. 1, which moves in a guideway *i*, extending transversely of the loom. This guideway has a transverse groove *i'*, corresponding with each of the tubes *c*, to accommodate the tube in its downward movement. The wire is guided from the drum by an eye *d''* in a frame *d'* and is kept from being loose on the drum by a spring-band *d'*, Fig. 2.

The mechanism for moving the drum to and fro through the shed comprises a slide *k*, also moving in the guideway *i*, a rod *k'*, connecting the slide with a cross-head *k''*, downwardly-extending projections *k''* *k'''* on the said cross-head and an endless traveling chain *k''* *k'''* on each side of a frame *k'''*, which supports bars *k''''*, whereon the cross-head *k''* slides. The endless chains are driven at a suitable speed in opposite directions, as indi-

cated by the arrows in Fig. 2, by sprockets *k''* *k'''* and carry each a tappet *k''''* *k'''''*. On a horizontal pivot on the slide *k* turns a hook *k''''*, which in the position shown in Fig. 2 is resting on the tooth of a crown-wheel *k''''*, turning on a vertical pivot carried by the slide. A pawl *k''''*, pivoted to a push-rod *k''''*, engages with ratchet-teeth on the periphery of the crown-wheel *k''''*. When in the course of its movement in the direction of the arrow the chain *k''* brings the tappet *k''''* against the projection *k''* on the cross-head *k''*, the latter is moved to the right, pushing the slide *k* until the push-rod *k''''* is pressed against the frame *d'*, which position of the parts corresponds with the disengagement of the tappet *k''''* and the projections *k''*. By coming against the frame *d'* the push-rod has been moved rearwardly against the pressure of spring *k''''* and has turned by its pawl *k''''* the crown-wheel *k''''*, causing the hook *k''''* to fall from its supporting-tooth and to take into an eye *d''* on the frame *d'*. Immediately afterward the tappet *k''''* strikes the projection *k''* on the cross-head *k''* and moves the latter back again, bringing drum *d* with it. The play of the hook *k''''* in the eye *d''* is such that the beginning of the backward movement of the head *k''* relieves the pressure of the rod *k''''* against the frame *d'*, thus allowing spring *k''''* to urge the rod forward, so that the pawl *k''''* takes into the next ratchet-tooth. The reciprocal action of the head *k''* just described occurs during a pause in the movement of the healds which may be produced in any known manner, and the next shed is not formed until drum *d* is at the end of the guideway *i* opposite to that at which it is shown in Figs. 1 and 2. By the time this next shed is formed tappet *k''''* has again come against projection *k''* and the cross-head *k''* is moved to push the drum *d* back into the position shown in Figs. 1 and 2. The play of the hook *k''''* in the eye *d''* causes the initial movement of cross-head *k''* in the forward direction to press the rod *k''''* against the frame *d'*, thus turning the crown-wheel *k''''* and causing the hook *k''''* to ride up to the top of the next tooth of the crown-wheel *k''''*, where it rests. In this position the hook is out of engagement with the eye *d''*, so that when tappet *k''''* brings cross-head *k''* back again the drum *d* is left behind. After the parts have resumed the position

shown in Figs. 1 and 2 the next shed is formed and the cycle of movements is repeated. The sprockets k^9 k^{10} are mounted on coaxial shafts and are driven from the main shaft of the loom (not here shown) through a sprocket l and gear l' .

Having thus described the nature of this invention and the best means I know of carrying the same into practical effect, I claim—

- 10 1. A shuttle-motion for a loom for heavy material comprising a guideway extending transversely of the loom, a slide adapted to move in the said guideway, a drum pivotally mounted on the said slide, and a second slide 15 adapted to move in the said guideway, a hook carried by the said second slide and adapted to engage the first-named slide, and means for moving the said second slide from end to end of the said guideway.
- 20 2. A shuttle-motion for a loom for heavy material comprising a guideway extending transversely of the loom, a slide adapted to move in the said guideway, a drum pivotally mounted on the said slide, a frame fixed to 25 the said slide, a device carried by the said frame to keep the weft-wire from becoming loose on the said drum, a device carried by

the said frame to guide the weft-wire and means for moving the said slide from end to end of the said guideway.

30

3. A shuttle-motion for a loom for heavy material comprising a guideway extending transversely of the loom, a slide adapted to move in the said guideway, a drum pivotally mounted on the said slide, a second slide 35 adapted to move in the said guideway, a hook pivotally mounted on the said second slide and adapted to engage the said slide carrying the drum, a crown-wheel mounted to rotate in a horizontal plane on the said 40 second slide and adapted to receive on its teeth or between them the said hook, means for rotating the said crown-wheel when the said hook is to engage and to disengage the said slide carrying the drum and means for 45 moving the said second slide to and fro in the said guideway.

In testimony whereof I have signed my name to this specification in the presence of two subscribing witnesses.

GIOVANNI GIUSSANI.
